United States Patent Office

Des. 206,496
Patented Dec. 20, 1966

206,496

BOTTLE

Arthur E. Giessinger, 8216 49th Ave. N.,
New Hope, Minn. 56034

Filed Oct. 22, 1965, Ser. No. 87,762

Term of patent 14 years

(Cl. D58—9)

The broken line showing a bottle cap in FIG. 3 is for illustrative purposes only.

I claim:

The ornamental design for a bottle, substantially as shown and described.
